UNITED STATES PATENT OFFICE.

JOHN H. LONSKY, OF DETROIT, MICHIGAN, ASSIGNOR TO THE IDEAL MANUFACTURING COMPANY, OF DETROIT, MICHIGAN, A CORPORATION OF MICHIGAN.

PIPE-FITTING.

987,807.

Specification of Letters Patent. Patented Mar. 28, 1911.

Application filed October 1, 1909. Serial No. 520,526.

To all whom it may concern:

Be it known that I, JOHN H. LONSKY, a citizen of the United States of America, residing at Detroit, in the county of Wayne and State of Michigan, have invented certain new and useful Improvements in Pipe-Fittings, of which the following is a specification, reference being had therein to the accompanying drawings.

10 The invention relates particularly to a soil pipe fitting designed for use at the base of a soil stack, and consists in the novel construction of a stack bend, and in the peculiar arrangement and combination of parts as

15 hereinafter described.

In the drawings,—Figure 1 is a vertical central section through a pipe fitting embodying my invention; Fig. 2 is a rear elevation thereof, partly in section; and Fig. 20 3 is a view in section and plan of the closure, the parts being detached.

A represents the main section of the fitting, or “elbow,” as it will be hereinafter termed, forming the connection between the 25 soil stack and sewer line, which in configuration is substantially a quarter bend. Connecting with the elbow and projecting upwardly therefrom beside the stack end of the fitting is a cleanout section B provided 30 at its upper end with a removable closure C. The purpose of this latter section is to permit the cleaning of the bend or the testing of the stack to be effected in the usual manner after the connection between the stack 35 and sewer has been made, which obviates the necessity heretofore existing of disconnecting the parts at the time of making the test.

The closure is of novel formation, and in 40 addition to serving as a cover or cap for the cleanout forms a means of connection between the latter and the usual testing hose. In construction, it comprises a plate or cover proper D having oppositely-disposed pairs 45 of separated lugs a formed on its under face and an annular groove b to receive a suitable gasket or packing c adapted to bear against an annular rib d on the end of the cleanout section.

E is a cross bar having a central opening 50 e and oppositely disposed projections f adapted to engage beneath corresponding lugs g upon the interior of the section B.

F is a nipple having screw-threads upon its opposite ends adapted to engage a screw-threaded opening h formed in the cover proper and projecting loosely through the aperture e, and G is a cap for closing the outer end of the nipple, the latter constituting 55 a hose connection.

H is a connection for an outside closet communicating with the interior of the bend or elbow proper preferably through the cleanout section B, as plainly shown in Fig. 1. For preventing the siphoning of the 60 closet trap, a vent connection I is formed in the fitting preferably within the side wall of the cleanout section, as shown, to which the usual vent pipe is connected.

I have shown the fitting in the form of a 70 unitary structure, and preferably provide a support or brace for the bend immediately beneath the upper or stack end of the fitting for supporting the stack. The support preferably comprises a depending lug or 75 stud J upon the lower wall of the fitting in the position described, a socket member K, and a support proper L formed of a section of pipe seated within the socket and loosely engaging the lug J, as shown. Such a support 80 maintains the fitting under the weight of the stack, and at the same time may be conveniently removed when desired in the installing of the bend.

From the foregoing description, it will be 85 seen that the bend is exceedingly simple in construction and obviates the necessity of using a number of fittings to form a connection between the stack and sewer. Furthermore, the cleanout section is in a convenient position to permit rodding or flushing 90 into the sewer, and by reason of the long sweep that is provided by the cleanout section and the lower portion of the bend proper the cleaning may be very readily effected.

What I claim as my invention is,—

1. A stack bend comprising an elbow

section having a stack fitting, a lateral closet connection, and a cleanout section positioned intermediate the stack fitting and lateral connection.

5 2. A stack connection comprising a main elbow section in the form of a quarter-bend, and a cleanout section formed integral with the elbow section, projecting upwardly

from the convex side of the bend and opening into the bend at a tangent thereto. 16

In testimony whereof I affix my signature in presence of two witnesses.

JOHN H. LONSKEY.
